DESIGN FOR A SPRING BALANCE

Thomas William Bache, West Bromwich, England, assignor to George Salter and Company Limited, West Bromwich, Staffordshire, England

Application April 5, 1934, Serial No. 51,315

Term of patent 7 years

To all whom it may concern:

Be it known that THOMAS WILLIAM BACHE, a subject of the King of Great Britain, residing at West Bromwich, Staffordshire, England, has invented a new, original, and ornamental Design for a Spring Balance, of which the following is a specification, reference being had to the accompanying drawing, forming part thereof.

Figure 1 of the drawing shows a perspective view

Figure 2 a plan view of a spring balance embodying my new design.

I claim:

The ornamental design for a spring balance, as shown.

In testimony whereof I have hereunto set my hand.

THOMAS WILLIAM BACHE.
